US0D1035362S

(12) **United States Design Patent** (10) **Patent No.:** **US D1,035,362 S**
(45) **Date of Patent:** **** Jul. 16, 2024**

(54) **DISPENSER**

(71) Applicant: **PepsiCo, Inc.**, Purchase, NY (US)

(72) Inventors: **Klaus Rosburg**, Brooklyn, NY (US);
Stephen Lim, Chappaqua, NY (US);
Gustavo De Souza Messias, Milan (IT); **Ali Akay**, Milan (IT); **Martin Ivar Franzen**, Milan (IT)

(73) Assignee: **PepsiCo, Inc.**, Purchase, NY (US)

(**) Term: **15 Years**

(21) Appl. No.: **29/907,788**

(22) Filed: **Jan. 9, 2024**

Related U.S. Application Data

(63) Continuation of application No. 29/894,460, filed on Jun. 9, 2023, now Pat. No. Des. 1,014,167, which is a continuation of application No. 29/801,135, filed on Jul. 27, 2021, now Pat. No. Des. 992,328.

(51) **LOC (14) Cl.** **07-01**

(52) **U.S. Cl.**

USPC **D7/308**

(57) **CLAIM**

The ornamental design for a dispenser, as shown and described.

DESCRIPTION

FIG. 1 is a top perspective view of a dispenser showing the claimed design;

FIG. 2 is another top perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the figures show portions of the dispenser that form no part of the claimed design.

1 Claim, 9 Drawing Sheets
